E. BUNZEL

GLAZING SPRIG

Filed March 15, 1926

INVENTOR
Ernest Bunzel
By W.W. Williamson Atty.

UNITED STATES PATENT OFFICE.

ERNEST BUNZEL, OF NORRISTOWN, PENNSYLVANIA.

GLAZING SPRIG.

Application filed March 15, 1926. Serial No. 94,699.

My invention relates to new and useful improvements in glazing sprigs, and has for its primary object to provide an exceedingly simple and effective device of this character which, when mounted in place will coact with panes of glass in such a way as to prevent endwise movement thereof.

Another object of the invention is to form a sprig from a single piece of metal fashioned to provide a body with a depending flange, said body coacting with the face of a glass to hold it in a glazing groove, while the depending flange coacts with the edge of the glass to prevent downward endwise movement thereof.

With these ends in view, this invention consists in the details of construction and combination of elements hereinafter set forth and then specifically designated by the

claim.

In order that those skilled in the art to which this invention appertains, may understand how to make and use the same, I will describe its construction in detail, referring by numerals to the accompanying drawings forming a part of this application, in which:

Fig. 1, is a perspective view of portions of a number of co-related glazing bars such as are used in green-houses, with a number of panes of glass shown held in place by my improved glazing sprigs.

Fig. 2, is an enlarged face view of a blank for forming one of the sprigs; and

Fig. 3, is a perspective view of one of the finished sprigs for use on the left hand side of a pane of glass.

Fig. 4, is a similar view of another of the sprigs for use on the right hand side of the pane of glass.

In carrying out the invention as herein embodied, 5 represents a number of glazing bars of a green-house, sash or the like having one or more glazing grooves 6 therein for the reception of the panes of glass 7, which are mounted after the manner of shingles so that the lower end of a succeeding glass overlaps the upper end of the preceding one.

It is necessary to hold the glasses firmly

in the frames or bars, and this is usually done with nail-like or flat sprigs, and oftentimes dependence is placed upon the pressure of the sprigs upon the glass to hold them in position, but for additional security, 55 others of these ordinary sprigs are sometimes placed at the ends of the glasses, but this requires considerable additional work and is more often dispensed with.

In my invention it is desired to provide 80 a sprig that will coact with the outer face of a glass in order to hold it in place under pressure, and also means that they will coact with the lower edge of the glass to prevent downward endwise movement thereof. 65 To this end, I form a blank 8 from suitable flat metal and fashion it so that the side edges 9 converge slightly outwardly away from the base 10 to a point intermediate the ends where they then abruptly converge to form a point 11. Next, one side of the blank is then bent at right angles upon the line 12 so as to form a body 13 and a depending flange 14, the forward edge of which is beveled as at 15, due to the angle 75 of the edge of the point. These several angles make it easy for the sprig to be driven into the woodwork of the sash, frame or glazing bars.

In practice the sprigs are made in right 80 and left handed ways as shown in Figs. 3 and 4, and are placed upon a pane of glass at the bottom exposed edge so that the body lies flat on the outer face of the glass and the flange overlies the edge thereof, and 85 when the sprig is driven into the woodwork the glass will be held in its groove by the body, and will be retained against downward endwise movement by the flange. This flange will also coact with the underneath 90 glasses which project beyond the bottom edge of the other glass, and assist in holding it in place. Where the glasses are of such length as to require additional fastening means, the use of flat-rail-like sprigs 95 may be used intermediate the ends of the glasses, a number of the flat ones being here shown and designated by the numeral 16.

Of course, I do not wish to be limited to the exact details of construction as herein 100

shown as these may be varied within the limits of the appended claim without departing from the spirit of my invention.

Having thus fully described my invention,
5 what I claim as new and useful is:

A glazing sprig formed from a flat piece of metal so fashioned as to have a base edge, two side edges slightly converging toward the ends furthermost from the base

and then abruptly converging to form a 10 pointed end, one side of said piece of metal being bent at right angles so as to provide a body with a depending flange, the forward edge of which is beveled.

In testimony whereof, I have hereunto 15 affixed my signature.

ERNEST BUNZEL.
